UNITED STATES PATENT OFFICE.

PETER J. P. SCHRAG AND ADAM J. SCHRAG, OF MCPHERSON, KANSAS.

FLAME REGULATOR FOR INCUBATOR LAMPS AND THE LIKE.

Application filed January 28, 1926. Serial No. 34,451.

This invention relates to flame regulators for incubator lamps and the like.

An important object of the invention is to provide a device of this character which may 5 be regulated from the usual thermostat and having means for controlling the flame by means of which the flame may be entirely cut off with the exception of a very small pilot flame.

10 A still further object of the invention is to provide a device of this character, the operating rod of which may be readily detached from the thermostat rod to thereby permit ready access to the wick and burner 15 for cleansing of the wick and trimming of the same or to permit the burner cap to be removed for a cleaning operation, if so desired.

20 A further object of the invention is to provide a device of this character which may be readily attached to a burner without in any manner altering the construction thereof and which may be operated from the usual control rod of an incubator.

25 These and other objects we attain by the construction shown in the accompanying drawings, wherein for the purpose of illustration is shown a preferred embodiment of our invention and wherein:—

30 Figure 1 is a vertical sectional view through the heating plant of an incubator, the lamp of which has applied thereto a flame control constructed in accordance with our invention;

35 Figure 2 is an enlarged side elevation of the wick tube having the flame control applied thereto, the burner cap being indicated in dotted lines;

Figure 3 is a section on the line 3—3 of 40 Figure 2, the parts being in the position which they assume when the flame is at its maximum height;

45 Figure 4 is a section similar to that shown in Figure 3, the parts in the position which they assume when the flame is at its minimum height;

Figure 5 is an enlarged detail section on the line 5—5 of Figure 3.

Referring now more particularly to the 50 drawings, the numeral 10 generally designates the wick tube of an incubator burner and 11 the cap of the burner having the usual slot 12 with which the wick tube aligns. As is well known to those familiar 55 with the art, the wick tubes of burners of this character are usually in the form of an

elongated oval. In accordance with our invention, we provide an adjustable band 13 adapted to clampingly engage the wick tube and having depending portions 14 for engaging the ends of the oval and providing supports for pivots 15. Upon the pivots 15 are each mounted a pair of arms 16, the upper ends of which engage with shutters 17 of a length equal to the length of the wick 60 tube upon its longer axis and provided centrally with a V-shaped notch 18. In applying the band to the wick tube, care is taken that the bases of these notches, when the band is in applied position and the shutters 70 17 are positioned against the sides of the wick tube, substantially align with the upper surface of the wick tube.

To two of the arms 16 at the same end of the attachment, a pair of links 19 are pivotally connected at their lower ends. The upper ends of the links 19 are preferably connected, as at 20, to the lower end of a socket 21 having a bayonet notch 22 for the reception of a pin 23 carried by the lower 80 end of a rod 24. The upper end of the rod 24 is adapted for engagement with the usual thermostatically controlled rod 25 of the incubator with which the device is to be employed and this rod has at its upper 85 end a series of openings 26 or is otherwise made adjustable as to length so that it may be properly engaged with the rod 25.

In the use of the device, when the temperature is low and the rod 25 accordingly 90 lowers, the shutters 17 will be moved to a position substantially as shown in Figure 3 and the usual operation of the burner will not be in any way interfered with. As the heating rises, these shutters approach the 95 upper end of the wick tube and finally in their highest position provide a continuation of the wick tube shutting off the flame from the wick at all portions thereof except at that portion of the wick lying at the 100 notches 17. These notches will supply sufficient air to permit continuation of flame from the wick at this point, thus providing a pilot light for relighting the wick when the incubator has again cooled. When it is 105 desired to cleanse the wick or to make adjustments of the flame of the burner, this may be accomplished by simply pressing downwardly upon the rod 25 or by rotating the rod 24 to disengage the same from the 110 socket 21. It will be seen from the foregoing that a device of this character may be

applied to the heating plant without in any manner changing the structure thereof and without in any manner interfering with the operation thereof except when the heat within the incubator becomes excessive.

It will also be understood that the construction hereinbefore set forth is obviously capable of a certain range of change and modification without materially departing from the spirit of the invention and we accordingly do not limit ourselves to such specific structure except as hereinafter claimed.

We claim:

1. In combination with a wick burner including the usual wick tube, an adjustable band clampingly engaging the wick tube and providing pivots at the opposite ends of the wick tube, a pair of arms pivotally engaged with each of said pivots, shutters carried by corresponding ends of said arms and operating means for said shutters, said shutters being movable about the pivots of the arms thereof to a position where they form

a continuation of the wick tube, the shutters being provided intermediate their ends with notches opening through their upper edges and of a depth such that they expose the upper end of the wick tube when in the last named position.

2. In combination with a wick burner including the usual wick tube, an adjustable band clampingly engaging the wick tube and providing pivots at the opposite ends of the wick tube, a pair of arms pivotally engaged with each of said pivots, shutters carried by corresponding ends of said arms and operating means for said shutters, said shutters being each provided centrally with a notch which, in the closed position of the shutters, substantially align at their lower ends with the upper surface of the wick tube.

In testimony whereof we hereunto affix our signatures.

PETER J. P. SCHRAG.
ADAM J. SCHRAG.
